ELECTRIC SWITCH-LOCK.

1,126,834.

Specification of Letters Patent.

Patented Feb. 2, 1915.

Application filed March 24, 1914. Serial No. 826,913.

To all whom it may concern:

Be it known that we, WALTER P. NEUBERT and WILLIAM E. SMITH, citizens of the United States, residing, respectively, at 5 Wilkinsburg, in the county of Allegheny and State of Pennsylvania, and at Pittsburgh, in the county of Allegheny and State of Pennsylvania, have invented certain new and useful Improvements in Electric Switch-Locks, of which the following is a specification.

Our invention relates to electrically controlled locks for railway switches.

Locks embodying our invention are particularly adapted for the control of outlying switches, that is, switches which are moved by a manual lever at the switch, the lock being electrically controlled from a distant point such as a signal tower, a telegraph station, or by a signal.

The present invention is an improvement on the lock shown in United States Letters Patent No. 914,447 granted to Walter P. Neubert on March 9, 1909.

One feature of the present invention is that the electromagnet which controls the lock is deenergized while the switch lever is locked, thereby eliminating the consumption of current by the device at such times.

We will describe one form of lock embodying our invention, and will then point out the novel features thereof in claims.

In the accompanying drawings, Figure 1 is a view showing in vertical section one form of lock embodying our invention. Fig. 2 is a sectional view on the plane indicated by the line II-II in Fig. 1. Fig. 3 is a view of a portion of the lock looking at the left-hand side of Fig. 1. Fig. 4 is a diagrammatic view showing one arrangement of circuit for controlling the lock by a signal. Fig. 5 is a plan view of a railway switch, and of an operating mechanism therefor including the lock shown in Figs. 1, 2 and 3. Fig. 6 is a side view of the operating mechanism and lock shown in Fig. 5.

Similar reference characters refer to similar parts in each of the views.

Referring first to Figs. 5 and 6, the reference characters 10, 10 designate the movable rails of a railway switch, which rails are connected, by a rod 11, with a switch operating device 11^a operated in turn by a switch operating lever 12. These parts may

be of any preferred construction, and may 55 be connected together in any desired manner, so that movements of the operating lever will cause movements of the switch rails.

Referring now to Figs. 1, 2 and 3, the locking mechanism is inclosed in and supported by a suitable casing comprising a base 13 and a body portion 13^a which parts are detachably connected together by bolts 13^b. Part of the mechanism is protected 65 by a cover 14 pivotally attached to the body portion 13^a by a pin 14^a. When the switch occupies the "normal" position and in which it is shown in Fig. 5 the lever 12 rests on a portion of the base 13 between the body 70 portion 13^a and two spaced standards 15, 15 integral with the base 13. Pivotally mounted between these standards on a pin 17 is a latch 16 having a handle 16^b and a nose portion 16^a, which latter, when the latch is 75 in either of the positions shown in Fig. 1, overhangs the lever 12 and prevents the latter from being lifted to move the switch. This latch is adapted to occupy three positions, viz., an intermediate position shown 80 in full lines in Fig. 1, one extreme position shown in dash lines in Fig. 1, and another extreme position in which its nose 16^a is swung downwardly out of the path of lever 12. The movements of the latch 16 are 85 controlled by means which we will now describe.

Pivotally mounted between the standards 15, 15 on another pin 20 is a member 19 whose upper end projects into the recess 21 90 in the under edge of latch 16. The lower end of this member is bifurcated and straddles the end of a rod 23 slidably mounted in base 13. Member 19 is pivotally connected with the rod by a pin 52 passing 95 through a slot 53 in each leg of the member. Screwed to the other end of rod 23 is a block 18 which is pivotally connected by a pin 25^a with a jaw 25^b forming part of a locking plate 25. As here shown, this plate 100 comprises a sleeve portion 25^c by which it is mounted to rock on a rod 35 which is mounted in the base 13 and is held in place by a cotter pin 35^a. The upper surface of plate 25 is provided with a notch or recess 105 26 adapted to co-act with a locking dog 27. This notch is elongated to permit the plate to rock through a limited angle when the

dog 27 is in locking position, for a purpose hereinafter explained. The dog 27 is formed on one end of a bar 28 the other end of which is fixed to one arm of an angle 5 lever 29 pivotally mounted on a pin 30 supported in lugs on a magnet bracket 32^a, which latter is attached to the body member 13^a. The other arm of angle lever 29 carries an armature 33 adapted to be attracted by an electromagnet 32 mounted in the bracket 32^a. When the magnet 32 is energized it will attract its armature and lift the dog 27 out of the notch 26, thereby leaving plate 25 free to rock, but when the 10 magnet is deenergized the dog 27 drops onto plate 25 and into the notch 26 when the latter moves into alignment therewith.

As long as the dog 27 is in the notch 26, plate 25 cannot be swung to the left any 20 farther than the position in which it is shown in Fig. 1, hence the rod 23 and member 19 then prevent latch 16 being raised far enough to unlock the switch lever 12. Any strain on the dog 27 caused by an attempt 25 to swing the latch 16 while the dog is in the notch will be taken up by a stop 38 which is attached to the body 13^a, thus preventing this strain being transmitted to the bar 28 or the pivot pin 30.

30 The sliding rod 23 is not mounted directly in the base 13, but slides in a sleeve 22 which in turn slides in suitable holes in the base 13. The movement of this sleeve in one direction is limited by the engagement of a 35 flange 22^a on the sleeve with a stop 31 screwed into the base 13. The sleeve is biased against this stop by springs 24 and 36. Fixed to the rod 23 is a collar 34 against which bears the spring 36 the other end 40 of which bears against a nut 22^a screwed into sleeve 22. The tendency of the latter spring is to hold the rod 23 and the parts connected therewith in the positions shown in full lines, these positions being the intermediate positions. When latch 16 is 45 depressed to the position shown in dash lines it moves rod 23 to the left against the action of spring 36, thereby swinging plate 25 so that the left-hand end of notch 26 lies under dog 27. Then if latch 16 is released it is 50 returned to the full-line position by spring 36. This movement of rod 23 independently of sleeve 22 is permitted by the space 40 between the block 18 and the end of sleeve 22, 55 and it will be seen that this movement of the parts may occur even when dog 27 is in the notch 26.

The plate 25 controls contacts in the following manner. Fixed to this plate is a 60 cam 37 which coacts with an arm 41 pivotally mounted at 41^a in a lug attached to a block 42 of insulating material, which block is mounted on arms extending upwardly from the bracket 32^a. This arm, when 65 raised, raises a grooved collar 45 of insulat-

ing material which slides vertically on a post 45^a mounted in block 42. A slot in one end of a contact spring 46 fits into the groove in collar 45, and the other end of this spring is fixed to the block 42. The 70 spring 46 carries a contact finger 46^a, which engages with a contact post 47 mounted in block 42. When plate 25 is in the position shown or is swung to the left from this position, cam 37 holds contact 46^a—47 closed, 75 but when the upper part of the plate swings to the right the cam allows this contact to open. This contact is employed to control magnet 32 as hereinafter explained. Fixed to spring 46 is a bar 48 of insulating material which supports and moves contact fingers 49 and 49^a which may be employed for any desired purpose.

The operation of the lock is as follows: When the parts are left to themselves, they 85 occupy the positions in which they are shown in full lines in Fig. 1. Contact 46^a—47 is then closed so that magnet 32 is energized (it being assumed that the contact which controls this magnet from a distant point is also closed) and dog 27 is therefore lifted from notch 26. If now latch 16 is depressed to the dash line position, plate 25 is rocked to the right, thereby opening contact 46^a—47, which deenergizes magnet 32 95 so that dog 27 falls into notch 26. The parts can then be locked in this position by passing a padlock 50 through a hole 16^c in latch 16, the lock bearing against the under surfaces of lips 15^a on standards 15. Then to 100 release the switch lever the operator presses on handle 16^b with his foot and removes the pad-lock. He then removes his foot from the latch whereupon the spring 36 moves rod 23 to the right, thereby moving 105 latch 16 to the full line position and moving plate 25 to the position shown. This closes contact 46^a—47, so that if the circuit for magnet 32 is closed at the distant point the magnet now becomes energized and moves 110 dog 27 out of notch 26. The operator now grasps the latch handle 16^b and swings it upwardly so that the nose 16^a moves out of the path of switch lever 12 and the latter is then free to be raised. During this movement, the lower end of member 19 engages 115 the nut 22^a, thereby moving sleeve 22 inwardly and so compressing spring 24. Then as soon as the operator releases latch 16 the parts are returned by spring 24 to 120 the positions shown.

It will be seen that when the lock is in the normal or locking position, that is, when the latch 16 is held down by pad-lock 50, magnet 32 is deenergized, hence the device is then 125 not consuming energy. This is an important feature of our invention. Another feature of importance is that after the operator removes the padlock from latch 16 he must remove his foot therefrom and then grasp the 130

latch with his hand. This change requires an interval of time during which the spring 36 moves the parts to their intermediate positions and magnet 32 raises dog 27. Hence, 5 this time interval insures that when the operator starts to swing the latch by hand the dog 27, will be out of the notch 26 and will therefore not bind against the right-hand end of the notch.

10 In order to retain the latch 16 and the plate 25 in the open or unlocking position, we provide a rod 39 (see Figs. 1, 5 and 6) one end of which is pivoted on a stud 39^a mounted on the lever 12 slightly below and 15 to the left of the center of the switch lever shaft 45. This rod is loosely supported to slide in an opening 42 in one of the standards 15 with its free end normally in close proximity to the member 19. When the 20 latch 16 has moved sufficiently to clear the lever 12 the member 19 will have moved out of the path of rod 39, and then when lever 12 is swung upwardly the rod 39 will be moved endwise in front of member 19 and 25 will lock the latter against return movement under the influence of spring 24. The rod 39 will remain in the locking position, even though it may move endwise, until the lever 12 is returned to the normal position. Lever 30 12 thus controls the return of the plate 25 to locking position, and as soon as the lever 12 has returned to normal position the rod 39 will be clear of member 19 and the spring 24 will then restore the parts to the normal 35 or locking position.

Attached to the base 13 is a bracket 43 in which slides a lock bar 44 connected with the switch rails as shown in Fig. 5. This bar is provided near one end with a notch or 40 recess to receive the switch lever 12 when the latter is in the normal position and to thereby lock the switch rails against movement by an outside force while the switch lever is in this position.

45 Referring now to Fig. 4, the switch A is moved by a rod 51 which is adapted to be reciprocated longitudinally. This rod is provided with a slot 51^a in which slides a rod 23 operatively connected with a plate 25 included in a lock embodying our invention. The connection here shown between the switch rails and the plate 25 is merely diagrammatic, the purpose of this view being to show how electromagnet 32 may be controlled by contact 46^a-47. It will be seen that while the dog 27 is in the notch 26 the plate 25 can be swung to open and close contact 46^a-47, but that this movement is not sufficient to fully withdraw rod 23 from slot 51^a. Magnet 32 is included in circuit with contact 46^a-47, and also with a contact 54 operated by a distant signal S' located in the rear of a home signal S which governs traffic over switch A. When signal S' is in the clear position, contact 54 is closed; then

if plate 25 is swung to the right as far as it is permitted by dog 27, contact 46^a-47 will be closed so that magnet 32 will be energized. Plate 25 can then be swung farther to the right, thereby withdrawing rod 23 from slot 51^a and so unlocking the switch.

Although we have herein shown and described only one form of lock embodying our invention, it is understood that various changes and modifications may be made 75 therein within the scope of the appended claims without departing from the spirit and scope of our invention.

Having thus described our invention, what we claim is:

1. In combination, a switch operating lever, a latch adapted to prevent movement of said lever, a plate operatively connected with said latch, a notch in said plate, an electromagnet, a dog controlled by said magnet for engaging said notch, means for biasing said latch and plate to an intermediate position, the said notch being of such length that it permits movement of the parts between said intermediate position and one extreme position when the magnet is deenergized but not in the other direction from the intermediate position unless the magnet is energized, a contact controlling said magnet which contact is controlled by the plate and 85 is closed or open according as the plate occupies the intermediate position or the first-mentioned extreme position, and means for locking said movable parts in the first-mentioned extreme position. 100

2. In combination, a switch operating lever, a latch adapted to prevent movement of said lever, a sliding rod operatively connected with said latch, a plate operatively connected with said rod, a notch in the plate, 105 an electromagnet, a dog controlled by said magnet and adapted to coact with said notch; means for biasing said latch and plate to an intermediate position comprising a sleeve slidably mounted on said rod, 110 a stop for said sleeve, a spring for biasing said sleeve against the stop, a collar fixed on said rod and a second spring acting on said collar and on said sleeve; the notch being of such length as to permit movement of 115 the parts to one extreme position from said intermediate position against the action of one of said springs when the dog is in the notch but to prevent movement in the other direction from said intermediate position 120 unless the dog is out of the notch; a contact controlling said magnet which contact is controlled by the plate and is closed or open according as the plate occupies the intermediate position or the first-mentioned extreme 125 position, and means for locking said movable parts in the first-mentioned extreme position.

3. In combination, a switch operating lever, a latch having an intermediate position 130

and two extreme positions and adapted to prevent movement of the switch operating lever when in the intermediate position and one extreme position but not when in the 5 other extreme position, a sliding rod, a plate connected with said rod to move therewith, a notch in said plate, an electromagnet, a dcg controlled by said magnet for engaging said notch, a sleeve slidably mounted on said 10 rod, a spring pressing upon said sleeve, a stop for said sleeve, a pivotally mounted member pivotally connected with said rod and adapted to press upon the sleeve in opposition to said spring, a collar fixed to said 15 rod, a second spring interposed between said collar and said sleeve, a surface on said latch operating when the latch is moved from the intermediate position to the first-mentioned extreme position to move said 20 member and the rod in one direction to compress the second spring, the sleeve being then held by said stop whereby the plate is then moved in one direction from an intermediate position, the notch being of such length 25 that said movement is permitted when the

dog is in engaging position, another surface on said latch operating when the latch is moved in the other direction from its intermediate position to move the member in the other direction, the member then engaging the sleeve to slide the rod and the sleeve in the other direction thereby moving the plate in the other direction and compressing the first spring; a contact controlled by said plate and closed when the plate occupies the intermediate position and when it is swung in the last-mentioned direction therefrom, but opened when the plate is swung in the first-mentioned direction, said contact controlling the electromagnet, and 30 means for locking the latch in the extreme position in which it prevents movement of the switch lever. 35

In testimony whereof we affix our signatures, each in the presence of two witnesses. 40
